HINGE

Eli M. House, Tampa, Fla., assignor to House Ladder Co., Inc., Tampa, Fla., a corporation of Florida

Application April 18, 1934, Serial No. 721,237
In Canada February 15, 1934

8 Claims. (Cl. 228—23)

This invention relates to hinges particularly of the type adapted to be used to connect the sections of a ladder to hold the sections in extended position for use as a straight ladder or in partially folded position as a step-ladder and the object of the invention is to provide a hinge of novel construction and design which permits the ladder to be readily and quickly converted into one type or other without removal of the hinge locking means, the same being a further development of the invention of my Patent 1,944,792 of January 23, 1934, all as will be more fully described and claimed.

Referring to the accompanying drawing, which is made a part hereof and on which similar reference characters indicate similar parts,

Figure 1 is a side elevation of the ladder in extended position, showing the hinge fixed thereto.

Figure 2 is an enlarged detail view of the hinge as in Figure 1.

Figure 3 is an end elevation of Figure 2.

Figure 4 is a section on line 4—4 of Figure 2, and

Figure 5 is a section on line 5—5 of Figure 2.

In the drawing reference character 10 indicates the side rails of the upper section of the ladder connected by a plurality of steps 11. The bottom section formed of side rails 12 are connected by a plurality of steps 13 and with a relatively wide step 14 located adjacent the upper ends which serves as a regular step when the ladder is used in extended position or as the top step when the ladder is partially folded for use as a step-ladder. Each side of the step 14 adjacent its rear edge is cut back as indicated at 15 to permit the side rails 11 to be folded against the side rails 12 for transportation or to be partially folded for use as a step-ladder. The steps of each section of the ladder are provided with suitable brace rods 16 under each and connected in any suitable manner to the side rails.

The lower section of the ladder is provided with a stay rod 17 adapted to engage in an eyelet 18 on the upper section when the ladder is used as a step-ladder and when the ladder is used in extended position it is secured along the side rail 12 by a clip 19. The step 14 is further supported, in addition to the rod 16, by a bracket 20 connected at one end by a nut and bolt 21 to the side rail 12 and at the other end by a nut and bolt 22 to the rear edge of the step, as clearly shown in Figure 2.

The sections of the ladder are connected together by means of hinges which will now be described. A plate 23 is secured by means of

bolts and nuts 24 to the outside of the lower end of the rail 10 and a similar plate 25 is likewise secured to the inside of the rail by means of the same bolts and nuts. Each plate is provided with a rearwardly extending flange 26 provided with aligned openings 27 therein to receive a hinge bolt 28. The plates and the end of the rail 10 are provided with an opening 29 therethrough, with the plate 23 threaded to receive and maintain a securing bolt 30 fixed in the opening.

The upper end of the rail 12 of the lower section is provided with a plate 31 fixed thereto by the nut and bolt 21, the rod 16 and an additional nut and bolt 32. The plate 31 is provided with a rearwardly and upwardly extending portion 33 which is provided with an opening 34 corresponding to the opening 27 to receive the hinge bolt 28. A slot 35 is formed in this portion in alignment with the opening 29 to receive the threaded end of the securing bolt 30. The sides 20 of the slot are curved slightly downward to permit the bolt to readily enter the slot since the bolt swings on a slight arc. The tips of the sides of the slot are provided with outwardly extending shoulders 36 against which a winged nut 37 is turned on the threaded end of the bolt 30 abuts to hold the sections in extended position. The shoulders may be formed by bending the metal which normally would be removed in cutting the slots 35 since there is ample stock for this purpose.

For the purpose of description only one hinge has been described and shown. It should be clearly understood that a like hinge is provided on the opposite side of the ladder.

It may be seen from the above description that the ladder with the hinge construction applied thereto may be readily converted from one type to the other as desired by simply unscrewing the winged nuts 37 until they will clear the shoulders 36 formed on the slots and then moving the sections to the desired position. The securing bolt 30 is maintained in place since it is threaded through the outer plate 23 on the upper section. It is possible, however, to secure the bolt in place 45 in other ways, one for example being to thread it through the plate 25 on the inside of the rail 10.

The hinge is not weakened in any way by the construction shown, particularly with reference to the slot since the pressure on the hinge bolt 50 is straight down. It has been found in tests that a single shoulder is ample to keep the ladder from folding but in order to make it safer and sturdier shoulders are provided on both sides of the slot.

The construction of the device described is such that when used in the manner above pointed out results in an improved hinge for a definite purpose, that of permitting a quick change to a particular type of ladder without sacrificing strength and one which can be produced at a minimum cost.

Having thus fully described my said invention, what I claim as new and desire to secure by Letters 10 Patent, is:

1. The combination with a ladder formed in sections of a hinge construction comprising a plate fixed to the end of one section, a second plate overlapping the first mentioned plate fixed 15 to the end of another section, a pin extending through said plates to hinge the sections together, a bolt extending through said first section being fixed with respect to the plate thereon, said second plate being provided with a slot adapted to 20 engage said bolt, stops formed on the edges of said slot, and means on said bolt adapted when turned thereon to abut said stops to lock said sections together in extended position.

2. The combination with a ladder formed in sections of a hinge construction comprising a plate fixed to the end of one section, a plate fixed to the end of the other section overlapping the first mentioned plate, a pin extending through said plates to hinge said sections together, a bolt extending through said first section and being fixed with respect to said plate on that section, a slot 25 formed in said plate on the other section adapted to engage said bolt when the sections are in extended position, outwardly turned stops formed 30 on the edges of said slot and a nut on said bolt adapted to be turned against said plate and abut said stops to maintain said sections locked together.

3. The combination with a ladder formed in sections of a hinge construction comprising a plate fixed to the end of one section, a plate fixed to the end of another section overlapping the first named plate, a pin extending through said plates to hinge said sections together, a bolt extending 45 through the first mentioned plate and the first mentioned section being fixed in one of said plates, a slot provided with outwardly extending shoulders along its edges formed in the plate on the

second mentioned section adapted to engage around said bolt when said sections are moved in straight line position, and a nut on said bolt adapted to abut said shoulders when turned on said bolt to lock said section in fixed position.

4. A hinge construction comprising a pair of overlapping plates, one of said plates being provided with a slot, means for hinging said plates together, and means for locking said plates in fixed position, said locking means including a 10 clamping member projecting through said slot and a shoulder extending along one edge of the slot and abutting said clamping means.

5. A hinge construction comprising a pair of overlapping plates, means for hinging said plates together, a bolt fixed to one of said plates, a slot formed in the edge of the other said plate adapted to engage said bolt, a nut on said bolt and stops formed on the edges of said slot to prevent relative movement between said plates when said nut 20 is turned on said bolt.

6. A hinge comprising overlapping plates, means for hinging said plates together, a bolt fixed to one of said plates, the other of said plates being provided with a slot formed in its edge 25 adapted to engage said bolt, a nut on said bolt, and means adjacent the edges of said slot adapted to limit turning of the plates with respect to each other when the nut is turned to contact said slotted plate.

7. A hinge comprising parallel plates pivoted together to swing in parallel planes, one of said plates being provided with a bolt fixed thereto and the other with a slot formed in the edge thereof adapted to engage said bolt, a nut on said bolt and stops formed on the edges of said slot adapted to lock said plates together when said nut is turned to contact the slotted plate.

8. A hinge construction comprising upper and lower parallel connecting plates hinged together, the upper plate being provided with a threaded 40 stub fixed thereto, the lower plate being slotted along its edge to engage said stub, a nut on said threaded stub and stops formed on the edges of said slot adapted to prevent relative movement between said plates when said nut is turned 45 to contact said upper plate.

ELI M. HOUSE.
